UNITED STATES PATENT OFFICE.

NORMAN L. SAMMIS, OF PROVIDENCE, RHODE ISLAND, ASSIGNOR TO HOME SERVICE, INC., OF PROVIDENCE, RHODE ISLAND, A CORPORATION OF RHODE ISLAND.

PACKAGE-DELIVERY DEVICE.

Application filed April 11, 1927. Serial No. 182,951.

My invention relates to a package delivery device adapted to deliver milk bottles or other packages in safety to the inside of a wall, usually the outside wall of a house 5 so as to prevent delivery men from coming in to the inside of the house.

A further object of my invention is to provide a device of this description, which may be readily set in place by the inhabitants 10 so as to receive packages therein and which may then be automatically locked by the delivery men against possible theft. A further object of my invention is to provide a device in which the package receptacle 15 may be lifted up on the inside of the wall portion so that fragile articles like milk bottles may be readily laid therein without any drop by the milk man, or other deliverant. A further object of my invention 20 is to provide a device of this description in which the package receptacle may be removed from the inside of the wall so as to substantially conceal its existence, the only portion then showing being the closed door. 25 A further object of my invention is to provide a package receptacle of a size and configuration for conveniently holding the usual articles normally delivered to a house.

In the drawings, Fig. 1 is a cross sectional view partially shown in elevation of 30 my invention attached to a wall portion with the door open and the package receptacle set to receive packages from without.

Fig. 2 is a similar sectional view of my invention with the door closed and the package receptacle lowered.

Fig. 3 is a front elevation of my invention attached to a service door.

Fig. 4 is a rear elevation of a service door 40 equipped with my invention with the package receptacle thereof removed.

Fig. 5 is a detailed view showing the detachable hinge I preferably employ to secure the package receptacle to the inside of the door.

Fig. 6 is a middle sectional view thereof.

In the drawings, wherein like characters of reference indicate like parts throughout, 50 generally indicates a suitable wall portion to which my invention is attached. In my preferred embodiment as shown said wall preferably comprises the back delivery door 10. Said door 10 is preferably provided within the delivery opening 12 there-

in. I provide the door 14 for said opening which is preferably of a size to completely close the opening 12, and I also provide means 16 to pivotally mount said door adjacent the opening so that it may conveniently 60 cover it, said means preferably comprising the hinge 16 mounted on the upper edge of said opening. I also provide means 18 attached to said wall portion to limit the forward movement of said door to the plane of 65 said wall portion 10. In my preferred embodiment said means 18 preferably comprises the frame 18 attached to the outer edge of said wall 10 and extending around said opening 12 to limit the forward movement of said door to the plane of the wall portion.

I also provide means attached to said door and the side of said wall opening to lock said door 12 in closed position against 70 opening from without. In my preferred embodiment said means includes the lug 17 projecting upwards from the lower edge of said opening and the spring catch 20 having the spring actuated end 22 projecting downwards 75 beyond the edge of said door 14 to engage said lug 17 to lock said door from opening from without. Said spring catch 20 is preferably provided with the withdrawing handle 24 operable from within to 80 release said catch.

I also provide means detachable from within said door to hold said door in open position and releasable from the outside of said door. In my preferred embodiment 90 said means preferably comprises the hook 26 suitably pivoted in the rear of said door and a rotatable shaft 28 projecting through said wall slightly above said door having the hooked inner end 30 adapted to engage 95 with said hook 26 on the rear of said door to hold said door in raised position and a handle portion 32 on said shaft on the outside of said wall to rotate said shaft 28 to release said hook 26 and hooked end 30 100 on rotation thereof to permit said door 14 by gravity to pivot to locked position. It is obvious that the falling of the door will cause sufficient momentum to cause the spring catch 20 to engage the lug 17 to prevent anyone from again opening the door from without.

It is apparent that the portion of my invention hitherto described provides a neat delivery opening for a wall portion which 110

may be locked by the deliverant on delivery of the package to prevent other persons from gaining access through said delivery opening.

I preferably provide, however, in combination therewith the package receptacle 40 and the means 42 to detachably pivotally attach said receptacle on the inside of said wall 10 below said opening preferably arranged so that when said receptacle 40 is in lowered position the outer edge thereof will abut the edge of said wall as shown in Fig. 2 and when in raised position it will be at an angle immediately behind said opening 12 so that fragile articles may be inserted therein by the deliverant without fracture thereof. As shown in Figs. 5 and 6 I preferably construct said pivoting means in such a manner that if desired the receptacle 40 may be readily detached from the inside of the door to present the inner wall surface shown in Fig. 4. Said means 42 preferably comprises the hinge brackets 41 attached to the inside of said wall 10 below said opening 12 having the hinge ears 43 projecting upwards therefrom supporting the hinge bars 45 therein, and the cooperating hinge brackets 47 attached to the upper outside edge of said receptacle 40 having the hinge hooks 49 projecting upwards adapted to be detachably hung on said hinge bars 45 between said ears 43.

I also provide means 50 attached to said receptacle and the inside of said wall to detachably secure said receptacle to said wall in raised position. In my preferred embodiment said means comprises the rearwardly projecting eye 52 attached to said wall 10 above said opening 12 and the hook 54 pivoted on the upper rear edge of said receptacle adapted to detachably engage with said eye 52 to detachably secure said receptacle to said door in raised position. The receptacle 40 is provided with the aperture 51 near the upper end of the rear edge thereof to permit access to the door 14 and its attachments for locking and unlocking purposes. Said aperture 51 forms the bar 53 extending horizontally across the upper rear edge thereof, said bar 53 and aperture 51 forming a convenient handle for readily lifting the receptacle 40.

In use the housewife or other inhabitant attaches the receptacle 40 through the medium of the hinge 42 adjacent the inside of the wall below the opening 12. When it is desired to use said receptacle for the delivery of fragile articles in particular, the housewife lifts the hook 26 and pivots the hooked end 30 of the shaft 28 so that it will project upwardly to engage the outer end of said hook 26 to hold said door in open position. If the door 14 is already locked by the spring catch 20 it is obvious that it is necessary for her to pull upon the

70 withdrawing handle 24 thereof to release it. She then raises the package receptacle 40 to the position shown in Fig. 1 and causes the hooked end 54 of said hook 50 to engage the eye 52 projecting rearwardly from the wall 10 above said opening 12 to retain said receptacle 40 in raised position behind the then open aperture 12. The milk man or other deliverant arrives and inserts the milk bottle 60 through the opening 12 into the package receptacle 40, the package receptacle 40 being so shaped that the milk man may readily insert his arm through the opening 12 to gently lay the milk bottle 60 on the bottom of said receptacle 40 as shown. He then turns the handle 32 of the shaft 28 to cause the inner end 30 thereof to become disengaged from the hook 26. It is then obvious that the door 14 through gravity drops into closed position being limited in its forward movement by the frame 18. It is apparent that it will stop in its forward movement substantially in the plane of the door 10, the momentum of the dropping door causing the end 22 of the spring catch 20 to raise up over the lug 17 against the force of the spring until it passes the lug 17 when the force of the spring 20 will push the latch 22 downward to cause the rear edge of the end 22 to engage the outer edge of the lug 17 to securely lock said door from opening from without. The housewife may then if she desires withdraw the hook 50 from the eye 52 and permit the receptacle 40 to gently drop to its lowered position shown in Fig. 2 when the milk bottle or other articles may be readily removed from the said receptacle. On gaining access through the aperture 51 she may again open and lock the door 14. If the delivery is 105 then completed for the day the housewife may remove the package receptacle as hitherto explained, or she may then set the package receptacle door and lock in the manner hitherto explained for another delivery. 110

It is obvious that I have provided a neat safe package delivery device simple to operate and easy to construct.

It is understood that my invention is not limited to the specific embodiment shown and that various deviations may be made therefrom without departing from the spirit and scope of the appended claims.

What I claim as new and desire to secure by Letters Patent is:

1. A package delivery device comprising in combination with a wall portion having a delivery opening therein, a door for said opening, means to pivotally mount said door adjacent said opening, means attached to said wall portion to limit the forward movement of said door to the plane of the wall portion, means attached to said door and the side of said wall opening to lock said door in closed position against opening from 130

- without, means attachable from within said door and releasable from the outside of said door to hold said door in open position, a package receptacle, means to detachably pivotally attach said receptacle on the inside of said wall below said opening so that when said receptacle is in lowered position it will abut the inside of said wall and when in raised position it will lie at an angle immediately behind said opening and means attached to said receptacle and the inside of said wall to detachably secure said receptacle to said wall in raised position. 2. A package delivery device comprising in combination with a wall portion having a delivery opening therein, a door for said opening, means to pivotally mount said door adjacent said opening, means attached to said wall portion to limit the forward movement of said door to the plane of the wall portion, means attached to said door and the side of said wall opening to lock said door in closed position against opening from without, a package receptacle, means to detachably pivotally attach said receptacle on the inside of said wall below said opening so that when said receptacle is in lowered position it will abut the inside of said wall and when in raised position it will lie at an angle immediately behind said opening and means attached to said receptacle and the inside of said wall to detachably secure said receptacle to said wall in raised position. 3. A package delivery device comprising in combination with a wall portion having a delivery opening therein, a door for said opening, means to pivotally mount said door adjacent said opening, a package receptacle, means to detachably pivotally attach said receptacle on the inside of said wall below said opening so that when said receptacle is in lowered position it will abut the inside of said wall and when in raised position it will lie at an angle immediately behind said opening and means attached to said receptacle and the inside of said wall to detachably secure said receptacle to said wall in raised position. 4. A package delivery device comprising in combination with a wall portion having a delivery opening therein, a door for said opening, means to pivotally mount said door on the upper edge of said opening, means attached to the outer edge of said wall portion extending across a portion of said opening to limit the forward movement of said door to the plane of the wall portion, a lug projecting upwardly from the lower edge of said opening, a spring catch having a spring actuated end normally projecting downwards to engage said lug to lock said door against opening from without and having a withdrawing handle operable from within to release said catch, a hook pivoted on the rear edge of said door, a rotatable shaft projecting through said wall above said door having a hooked inner end adapted to engage with said hook on the rear edge of said door to hold said door in raised position and a handle on the outside of said door to rotate said shaft to release said hook and hooked end to permit said door to pivot to locked position.
- In testimony whereof I affix my signature.
NORMAN L. SAMMIS.
